[57] CLAIM

The ornamental design for a bottle, or similar article, as shown and described.

DESCRIPTION

FIG. 1 is a front elevational view of a bottle, or similar article, showing my new design;
FIG. 2 is a rear elevational view thereof;
FIG. 3 is a side elevational view thereof;
FIG. 4 is a top plan view thereof;
FIG. 5 is a bottom plan view thereof; and
FIG. 6 is an elevational view similar to FIG. 2 on a reduced scale showing a modified form of my new design wherein all five sides are the same in appearance.
